UNITED STATES PATENT OFFICE.

ANDRÉ M. MERTZANOFF, OF NEW YORK, N. Y., ASSIGNOR TO AMERICAN RADIATOR COMPANY, OF NEW YORK, N. Y., A CORPORATION OF NEW JERSEY.

BOILER.

Application filed October 5, 1925. Serial No. 60,698.

My invention relates to improvements in heating apparatus and the same has for its object more particularly to provide a boiler in which the complete combustion of the fuel will be smokelessly effected.

Further said invention has for its object to provide a boiler embodying novel means whereby the secondary air required to effect the complete combustion of the fuel is introduced into the boiler at the lowest practical temperature.

Further said invention has for its object to provide a boiler in which the secondary air necessary to effect the complete combustion will, due to its introduction at such relatively low temperature into the combustion chamber containing the relatively lighter hot combustible gases, be caused to attain a high velocity or rate of flow, and be brought more or less forcibly into contact with the bed of incandescent fuel, and with the hot gases and products of combustion emanating therefrom.

Further, said invention has for its object to provide a boiler in which the secondary air is introduced into the boiler through a transverse duct having a long, relatively narrow outlet, by means of which the temperature differential between the air in said duct and the gases within the combustion chamber is utilized to convert the pressure head of said air into velocity or rate of flow in order to effect the due mixture of said air with the combustible gases to effect complete combustion.

Further, said invention has for its object to provide a boiler in which the secondary air required to effect the complete combustion of the fuel is caused to be discharged into the combustion chamber in the form of a broad band extending transversely entirely across the fuel receptacle adjacent to the rear end of the grate, and brought forcibly into intimate mixture with the products of combustion.

Further, said invention has for its object to provide a boiler in which the secondary air is conducted to a central point within the boiler and then uniformly discharged transversely across the fuel bed and mixed with the products of combustion as the same pass from the combustion chamber to the flues.

Further, said invention has for its object to provide a boiler in which the secondary air is introduced into the boiler by way of a relatively wide transverse duct, extending en-

tirely across the boiler, having opposing wall portions oppositely curved to form a constricted outlet producing a Venturi tube action or effect.

Further, said invention has for its object to provide a boiler in which the secondary air is conducted into the boiler and to the central part of a transverse duct having a relatively narrow longitudinal discharge opening therein in order that the volume of air entering said duct may be caused to issue from said discharge opening at high velocity and be projected forcibly, in the form of a downwardly flaring band, against the bed of incandescent fuel, and into intimate contact with the combustible gases and products of combustion passing between said duct and the bed of fuel.

Further, said invention has for its object to provide a boiler in which the secondary air is introduced into the boiler through transverse and longitudinal ducts and forcibly discharged therefrom in the form of downwardly flaring transverse and longitudinal bands or sheets against the bed of incandescent fuel, and into intimate contact with the combustible gases and products of combustion passing towards the flues.

Further, said invention has for its object to provide a boiler with novel means whereby secondary air at a relatively low temperature is introduced into the boiler from the rear thereof and caused to be discharged through longitudinally arranged outlets directly into the rear part of the combustion chamber.

Other objects will in part be obvious and in part be pointed out hereinafter.

To the attainment of the aforesaid objects and ends my invention consists in the novel details of construction, and in the combination, connection and arrangement of parts hereinafter more fully described and then pointed out in the claims.

In the accompanying drawings forming part of this specification, wherein like numerals of reference indicate like parts—

Figure 1, is a front elevation showing one form of boiler constructed according to, and embodying my said invention;

Figure 2, is a rear end elevation;

Figure 3, is a vertical longitudinal section on the line 3—3 of Fig. 1;

Figure 4, is a horizontal section on the line 4—4 of Fig. 3;

Figure 5, is an enlarged detail perspective view showing the form of the secondary air duct; and

Fig. 6 is a rear end elevation of a modified form of boiler.

In said drawings 10 designates a boiler of the sectional type comprising a hollow front section 11, a hollow back section 12, and a plurality of hollow intermediate sections 13.

10 The said front, back and intermediate sections are communicatively connected at their upper and lower portions by nipples 14, in the usual manner.

The front section is provided with the usual flue openings 15, fuel opening 16, slicing opening 17, and ash pit opening 18 which are respectively provided with doors 15' 16' 17' 18'. The back section is provided with a smoke outlet 19 over which is secured a 20 flanged smokehood 19'.

Each intermediate section 13 is here shown in the form of an endless loop having hollow vertical portions 20, forming the side walls of the boiler, and hollow horizontal top and bottom portions 21, 22, respectively. The intermediate sections 13 are further each provided with registering hollow transverse members 23 which jointly form the crown sheet or top of the combustion chamber. Intermediate 30 said transverse members 23 and the top transverse members 21 are the longitudinally extending outer and intermediate flues 24^a and 24^b. The hot gases and products of combustion are caused to pass upwardly at the rear of the combustion chamber into the said flues 24^a, and forwardly therein from the rear of the boiler, and thence rearwardly through the center flue 24^b to the smoke outlet 19.

40 Adjacent to the rear end of the boiler two adjoining intermediate sections 13 are provided with integrally formed depending hollow members 26, which are arranged in spaced relation parallel to each other, and extending entirely across the interior space or 45 combustion chamber at the rear of the grate.

The said depending members 26 have their opposing wall portions 27 adjacent to their lower edges curved inwardly towards each other to form a constricted outlet terminating 50 in a gradually flaring mouth which communicates with the secondary air space or flue formed between said depending members 26.

The secondary air is conducted to the air duct formed between said members 26 by way 55 of a passage or conduit 28 comprising the aligned openings 28^a having registering flanges 28^b and formed centrally in the rear member 26, the back section 12, and the intermediate sections 13 interposed between said 60 back section 12 and the rear depending member 26, which openings 28^a form a duct having water cooled walls extending longitudinally of the furnace from the back section 12 to the rear depending member 26 through 65 which the secondary air is admitted.

As the secondary air is admitted into the furnace at a comparatively low temperature, and as the heated gas and products of combustion within the combustion chamber possess a relatively high temperature the secondary air partly due to said differential in temperature and partly due to the tension of the draft, will be caused to issue under pressure or suction with great velocity and impinge or mushroom upon the incandescent fuel upon the grate directly below said air duct, and thus become intimately mixed with the hot gases and products of combustion as they pass from the combustion chamber to the flues.

70 Further, the secondary air is delivered into the transverse air duct at a point midway of its ends, and caused completely to fill said duct, as a result of which the air will be discharged evenly and uniformly through the 75 entire length of the constricted outlet, in the form of a continuous sheet through which and with which the hot gases and products of combustion must pass after leaving the combustion chamber, and thus insure the complete 80 combustion of the fuel.

85 When it is desired to supply secondary air to the rear of the depending members 26, which may become desirable at times in the larger sizes of boilers, the conduit 28 may be 90 provided with a number of small apertures or constricted outlets 30 as shown at Figs. 4 and 5 which are preferably formed partly in each of two opposing boiler sections and arranged in fan-shaped formation to effect the 95 discharge of the air in fan-shape extending entirely across the boiler at the rear of said depending member 26. The openings or outlets 30 are constricted like the outlet between the members 26, to produce a Venturi-tube 100 effect, and are arranged longitudinally so that the air issuing therefrom is flared out transversely to distribute the same uniformly from one side of the boiler to the other.

105 The admission of secondary air to the ducts 110 or passages is controlled by means of a closure 31 hinged at 32 over the inlet or opening 28^a at the back of the boiler. A sector 33 secured to said closure is engageable with the edge of the opening to permit of the closure being 115 held to different positions of adjustment whereby to control the amount of air admitted to the secondary air ducts.

120 At Fig. 6 is shown a form of boiler in which the secondary air is admitted to the boiler from both the sides and the back. The closures 31^a, similar to the closure 31, are provided to control the amount of air admitted to the secondary air duct from the opposite sides of the boiler.

125 Having thus described my invention, what I claim and desire to secure by Letters Patent is:

1. In a heating apparatus of the character described, means for supplying secondary air 130

- thereto comprising a water-backed duct arranged across the apparatus above and adjacent to the rear of the fuel bed and composed of separate, spaced, depending water-backed members communicating at their ends and upper intermediate portions with the water spaces of the boiler; said duct having its lower opposing wall portions tapering inwardly towards each other to form therebetween a relatively narrow, longitudinal discharge opening, substantially as specified.
2. In a heating apparatus of the character described, means for supplying secondary air thereto from without comprising two transverse depending water-containing members substantially coextensive in length with the width of the apparatus having all of their wall portions exposed and water-backed; said members communicating at their ends and upper intermediate portions with the water spaces of the apparatus and forming therebetween a duct extending across the combustion chamber above and adjacent to the rear of the fuel bed; the lower opposing wall portions of said duct tapering inwardly towards each other to form therebetween a constricted, longitudinal discharge opening at the base thereof for directing said secondary air in the form of a continuous sheet downwardly upon the bed of incandescent fuel and to mingle with the gases and products of combustion as the same are about to pass between said duct and the fuel bed, substantially as specified.
3. A boiler of the character described comprising a plurality of transverse sections communicatively connected; certain of said sections above and adjacent to the rear of the bed of fuel each having a depending water-containing member communicating at its ends and upper intermediate portions with the water spaces of the boiler; said members being arranged in spaced relation to form therebetween a transverse duct having a longitudinal discharge opening at its base, substantially as specified.
4. A boiler of the character described comprising a plurality of transverse sections communicatively connected; certain of said sections each having a depending water-containing member communicating with the water spaces of the boiler; said members being arranged in spaced relation to one another to form therebetween a transverse duct, and having their lower opposing wall portions extending towards each other to form therebetween a relatively narrow, longitudinal discharge opening, substantially as specified.
5. A boiler of the character described comprising a plurality of transverse sections communicatively connected; certain of said sections each having a transverse depending, water-containing member substantially coextensive in length with the width of the
- boiler and communicating at its ends and upper intermediate portion with the water-spaces of its respective boiler section; said members being arranged in spaced relation parallel to one another to form therebetween a duct extending across the combustion chamber above and adjacent to the rear of the bed of fuel for conducting secondary air from without the boiler, and having lower opposing wall portions curved inwardly towards each other to form a constricted, longitudinal discharge opening, and thence curved outwardly to form a gradually widening mouth for said constricted discharge opening, substantially as specified.
6. In a heating apparatus of the character described, means for supplying secondary air thereto comprising a duct having water-backed wall portions formed integrally with the walls of said apparatus and communicating with the water spaces thereof and arranged transversely of the apparatus above and to the rear of the bed of fuel and having a relatively narrow, longitudinal discharge opening at the base thereof, and water-backed means formed integrally with the walls of said apparatus and communicating with the water spaces thereof for conducting secondary air to said duct at a point centrally between the ends thereof, substantially as specified.
7. In a heating apparatus of the character described, means for supplying secondary air thereto comprising a duct extending transversely across the apparatus and composed of two similarly shaped depending water containing members communicating with the water spaces of the apparatus and arranged in spaced relation to one another; said members having their lower opposing wall portions extended towards each other to form therebetween a relatively narrow, longitudinal discharge opening, substantially as specified.
8. In a heating apparatus of the character described, means for supplying secondary air thereto comprising a duct extending transversely across the combustion chamber and adjacent to the rear of the grate, said duct consisting of two similarly shaped depending water containing members communicating with the water spaces of the apparatus and arranged in spaced relation to one another; said members having their lower opposing wall portions extended towards each other to form therebetween a relatively narrow, longitudinal discharge opening, substantially as specified.
9. In a heating apparatus of the character described, means for supplying secondary air thereto comprising a duct extending transversely across the combustion chamber adjacent to the rear of the grate, said duct consisting of two similarly shaped depending water containing members communicating

with the water spaces of the boiler and arranged parallel and in spaced relation to each other; said members having the opposing wall portions adjacent to their lower edges curved inwardly towards each other to form a constricted outlet opening, and thence curved outwardly to form a transversely gradually widening mouth for said constricted discharge opening, substantially as specified.

10. A boiler of the character described comprising a front, back and a plurality of intermediate sections communicatively connected, certain of said intermediate sections adjacent to the rear of the grate each having a depending water-containing member communicating with the water spaces of the boiler and arranged parallel in spaced relation to form therebetween a transverse duct having 15 a constricted discharge opening at its base, and one end section and the intermediate sections between said end section and an intermediate section whose depending member forms a wall of said duct having registering openings therein forming a passage for conducting air into said duct, substantially as specified.

11. A boiler of the character described comprising a front, back and a plurality of intermediate sections communicatively connected, 20 certain of said intermediate sections adjacent to the rear of the grate each having a depending water-containing member communicating with the water spaces of the boiler and arranged parallel in spaced relation to form therebetween a transverse duct having a constricted discharge opening at its base, and said back section and the intermediate sections between said back section and the intermediate section whose depending member forms the back wall of said duct having 25 registering openings therein forming a passage for conducting air into said duct, substantially as specified.

12. A boiler of the character described 30 comprising a front, back and a plurality of intermediate sections communicatively connected, certain of said intermediate sections adjacent to the rear of the grate each having a depending water-containing member com-

municating with the water spaces of the boiler and arranged parallel in spaced relation to form therebetween a transverse duct having a 50 constricted discharge opening at its base, and said back section and the intermediate sections between said back section and the intermediate section whose depending member forms the back wall of said duct having registering openings therein forming a longitudinal passage extending from the back end of the boiler for conducting air to said duct at 55 a point intermediate the ends thereof, substantially as specified.

13. In a heating apparatus of the character described, means for supplying secondary air thereto comprising a water-backed duct arranged transversely of the apparatus and having an opening therein for the discharge of secondary air, and a water-backed duct arranged centrally above the rear end of the grate, extending longitudinally of the boiler 60 from the back thereof, communicating with said first named duct centrally thereof, and having a plurality of outlets therein arranged longitudinally thereof; each of said outlets having opposing wall portions tapering inwardly towards each other to form a 65 constricted longitudinally extending opening, and thence curved outwardly to form a gradually widening mouth for said constricted opening, substantially as specified.

14. In a heating apparatus of the character described, means for supplying secondary air thereto comprising a water-backed duct arranged transversely of the apparatus above the grate and having a discharge opening 70 therein, and a water-backed duct extending longitudinally from the back of said boiler and communicating with said first named duct centrally thereof for supplying secondary air thereto; said second named duct having a plurality of outlets therein for discharging secondary air into the combustion chamber to the rear of said first named duct, substantially as specified.

State of New York, this 3d day of July, 95
1925.

ANDRÉ M. MERTZANOFF.
